LUMINAIRE

Donald W. Harling, Milwaukee, Wis., assignor to McGraw-Edison Company, Milwaukee, Wis., a corporation of Delaware

Filed May 8, 1964, Ser. No. 79,885

Term of patent 14 years

(Cl. D48—31)

Fig. 1

Fig. 2

Fig. 3

Fig. 4

Fig. 5

FIG. 1 is a right side elevational view of a luminaire embodying the instant invention;

FIG. 2 is a top plan view of the luminaire shown in FIG. 1;

FIG. 3 is a front elevational view of the luminaire shown in FIG. 1;

FIG. 4 is a left side elevational view of the luminaire shown in FIG. 1; and

FIG. 5 is a bottom view of the luminaire shown in FIG. 1.

The dominant feature of my design resides in the portion shown by full lines.

I claim:

The ornamental design for a luminaire, as shown and described.
